UNITED STATES PATENT OFFICE.

JAMES M. ROBINSON, OF SIOUX CITY, IOWA.

PROCESS AND APPARATUS FOR CLEANING RADIATORS.

Application filed April 16, 1928. Serial No. 270,502.

My invention relates to the art of radiator cleaning and has for its object to provide a method of removing the scale, sediment and other foreign matter from the interior of a 5 radiator that has been in use for a considerable length of time, so as to open the radiator passages.

The lime and foreign matter in ordinary water will eventually clog the passages of 10 a radiator to such an extent that the radiator will no longer carry the full load of the water pump and will not cool the motor sufficiently to keep it at a safe operating temperature during fast driving.

More particularly, it is my object to provide a method of cleaning radiators employing 15 a caustic solution, heating the solution and forcing it through the radiator passages.

A further object of my invention is to provide a method in which the flowing of the 20 solution through the radiator passages will dislodge the foreign material which has become deposited therein as a sediment, by its force of flow.

A further object of my invention is to provide a method in which the sediment can be quickly removed from the radiator after 25 being dislodged by the solution without losing any of the solution and without allowing any of the sediment to again become lodged in the radiator passage.

My invention further contemplates a process 30 in which the operator is able to watch the progress of the removal of scale and foreign matter so that he may immediately be aware of the fact that the passages have been fully cleared.

Another object of my invention is to provide 35 a process which will not injure the metal of the radiator.

Finally, my object is to provide a process adapted to be completed in a minimum length 40 of time.

My invention further involves the providing 45 of a machine adapted to carry out the process of my invention and particularly to provide it with a simple and novel device for both regulating the load which the 50 motor of the machine carries and also for apprising the operator of the progress of the process.

With these and other objects in view, my 55 invention consists in the construction, arrangement and combination of the various parts of my device, whereby the objects con-

templated are attained, as hereinafter more fully set forth, pointed out in my claims, and illustrated in the accompanying drawings, in which:

Fig. 1 is a plan view of the machine with a portion of the cover broken away.

Fig. 2 is a side elevation of the machine, with a radiator attached, illustrating the method of carrying out the process.

Fig. 3 is a plan view of the machine with the tank removed.

Fig. 4 is a vertical, sectional view of the machine, taken on the line 4—4 of Fig. 2.

The cleaning of a radiator which has become clogged presents a number of problems. The entire interior surface of the radiator channels in a radiator which has been used for a length of time are encrusted with a lime scale. In addition to this, the upper 70 extremities of the passages are clogged with mud, bits of débris, and other foreign material which has become lodged between the walls of the channels. This deposit of foreign matter very rarely extends below a 75 depth of $\frac{3}{4}$ of an inch from the bottom of the radiator tank. Since it is composed of all sorts of materials including metallic substances, insoluble substances, and the like, it would be impossible to find a solvent for all 80 of these materials which would not also dissolve the metal of the radiator channels.

It has been known for a considerable length of time that a proper solution of chemicals would remove the scale from a radiator without injuring the metal and I do not consider this to be new in my invention. However, the removing of the scale is only a partial solution of the problem of cleaning a radiator. To remove this scale which has become 95 very firmly encrusted upon the walls of the radiator channels requires more than mere mechanical agitation. To remove the foreign material requires more than the use of a chemical solution.

In my process, both of these things are accomplished simultaneously by the action of the same agent. I employ a chemical solution, heated to increase its activity and forced through the channels of the radiator by 105 positive pressure so that the resistance of the sediment deposit may not overcome the flow of the liquid.

Before proceeding further with a description of my process, however, it may be better 110 understood by contemplating the machine in which that process is carried out.

A supporting frame structure comprises the forward and rear legs 10 and 11, respectively, connected at their upper ends by side rails 12 and near their lower ends by side rails 13. The rails 13 extend forwardly as at 14 to provide a support for a radiator 15.

The side rails 12 are connected at their ends by upper cross rails 16 and the legs 10 and 11 are connected near their lower ends by lower 10 cross rails 17 and 18, respectively. The outer ends of the extended portions 14 are connected by a cross rail 19.

Supported between the rails 12 is a tank 20, which has flanges 21, extended outwardly 15 to engage the rails. A cover 22 is provided to completely cover the tank and has an opening 23, in which is supported a funnel 24 provided with a sediment screen 24a.

A pump 25 is supported upon the cross rail 20 17 and an intermediate cross rail 26 and is connected to the tank 20 by its intake pipe 27, the tank discharge pipe 28 and an intervening valve 29, controlled by a hand wheel 30.

A motor 31 is supported upon intermediate 25 cross rails 32, secured to the lower longitudinal rails 13, and is provided with a drive pulley 33, connected to a drive pulley 34 on the pump by means of a belt 35. The belt drive is used as a safety measure against possible 30 breakage, due to overloading of the pump.

The outlet 36 of the pump is connected by an elbow 37 to a laterally extending discharge pipe 38, which brings the discharge connection 35 of the pump to the side of the machine where it will be opposite the return connection 39 of the radiator 15.

It may be stated at this point that the radiator is supported in an inverted position between 40 the arms 14 with its hose connections facing the machine. The purpose of this arrangement will be more fully explained hereinafter.

The discharge pipe 38 is connected by an 45 elbow 40 to an upwardly extending pipe 41, which in turn is connected by an elbow 42, having a nipple end 43, to a sleeve 44, which is threaded upon the nipple 43. Where a very small radiator connection is encountered, the nipple 44 may be removed. A flexible 50 hose 45 is employed to connect the nipple 44 with the discharge connection 39.

The tank connection 46 of the radiator is connected by a flexible hose 47 to the funnel 55 24, the hose being simply draped over the edge of the funnel and allowed to extend into the same.

The solution in the tank has been indicated in Fig. 4 by the reference character 48. This 60 solution is composed of the following ingredients: 3 lbs. soda ash, 4 oz. lye, $\frac{1}{2}$ lb. sal soda, 4 gal. water.

A heater 50 is supported upon a platform 51, secured to the cross rail 18, and is connected 65 by an intake pipe 52 to the bottom of

the tank 20 and by a return pipe 53 to the end of the tank near the top thereof. The heater shown is a gas heater of a common type and is very efficient for the purpose for which it is used. It will be understood, however, that a simple burner, positioned underneath the tank and applying its heat directly to the tank, might be substituted effectively for the heater shown.

In the operation of the process, the radiator 15 is removed from the vehicle and placed in the inverted position already described and shown in Figs. 1 and 2 with the discharge pipe from the pump connected to the return connection from the radiator and the return pipe to the tank 20 connected to the tank connection 46. The solution is heated to a temperature approaching the boiling point and the motor is started, causing the pump to deliver the solution to the radiator. 75 The pump 25 is a positive pressure pump. The effect upon the pump of the resistance of the radiator channels to the flow of liquid will be to regulate the speed of the pump. The pump will be constrained to operate at the speed at which it can deliver the amount of solution which it is receiving through the intake pipe 27. Thus with the valve 29 only 80 opened a slight amount at the beginning, the pump will be able to operate close to the maximum speed of the motor 31. In practice, the valve is opened sufficiently so that the pump and motor will labor. When thus laboring it will deliver a more forceful flow of solution to the radiator than if it were passing only 90 the amount of solution per minute which could freely circulate through the radiator.

As the solution gradually cleans out the channels of the radiator, the operator opens the valve, at intervals, so as to keep the pump and motor laboring. This accomplishes two important functions. In the first place, as has already been brought out, the pump will 105 positively force as much solution through the radiator per minute as the power of the motor will determine and this forced flow will act mechanically upon the particles wedged between the walls of the radiator channels to force them out. In the second place, the laboring of the pump and motor are easily detected by the operator and furnish a clue to advise him of the freedom of circulation of the solution through the radiator. The pump and valve are so coordinated that when the valve is completely opened and the pump is 110 thus delivering a full stream to the radiator, the pump will be traveling at substantially its full rate without laboring, provided that the radiator channels have been completely cleared. It will be understood that the coordination of the pump and the valve, in relation to the channels of the radiator, cannot be made entirely accurate for the reason that radiators will vary in their capacity. For 115 truck radiators, assuming the machine to 120 125

have been set for a smaller radiator, the full freedom of flow will be reached before the radiator has been completely clear and it will be necessary to allow the machine to operate 5 for a further length of time, proportional to the amount of time required to obtain the full freedom of flow. However, for any particular class of radiators such as, for instance, those used on the ordinary, medium-priced 10 passenger vehicle, the pump and valve may be set for this particular class of radiators so as to indicate definitely the moment the radiator has been entirely cleared.

Summing up briefly the foregoing discussion of the functions of the valve and motor, the theory of operation is as follows: The changing capacity of the radiator caused by the gradual removal of the sediment cuts down its resistance to the flow of the solution. 15 The opening of the valve increases the load upon the motor. The decrease of the resistance of the radiator correspondingly decreases the load upon the motor. The load which the motor is carrying can be determined by the speed of rotation, or, as it is commonly termed, the laboring of the motor. The operator can thus regulate the stream of solution, so as to exert a constant force against the radiator by gradually opening the valve 20 and keeping the motor laboring substantially the same amount. When the motor has ceased to labor after the valve has been fully opened, the resistance of the radiator has been cut down to a minimum.

25 The radiator overflow pipe is plugged in order to retain the pressure and the filling cap 60 is tightly closed for the same purpose.

It may now be noted that my process provides a constant flow of liquid from the bottom of the radiator to the top thereof (the radiator being inverted and the flow being downwardly), as indicated by the arrow 61. There are three important elements of process here involved. In the first place, the flow 30 is in the reverse direction to the normal flow of water through the radiator. Thus the deposit of foreign material, which is seldom more than $\frac{3}{4}$ of an inch deep, is forced out in the direction from which it entered the 35 radiator channels.

In the second place, the flow is constantly in the same direction so that there may be no tendency of the forced flow of solution to force the particles any further in the direction in which they originally entered the 40 radiator channels.

It may be noted that the constant flow in a direction reverse to that of normal flow is essential only during the dislodging of 45 sediment.

In the third place, the radiator is inverted so that the particles as they are forced out will drop into the open tank 62, which is below the channels when the radiator is in its 50 inverted position.

With the particles thus deposited in the tank 62, which acts as a sediment trap to prevent the particles flowing back into the tank 20 after the radiator has been cleared, the sediment may be flushed out by removing the 70 cap 60 and attaching a water hose to either one of the connections. Before this is done, however, the radiator is tipped up sufficiently to allow the solution remaining in the tank 62 to flow through the connection 46 into the 75 funnel 24.

Summing up the essential elements of my process, it will be seen that they are as follows:

1. Using a solution adapted to remove 80 scale without attacking the metal of the radiator.

2. Forcing the solution through the radiator under positive pressure.

3. Regulating the load by means of a 85 valve.

4. Forcing the solution constantly through the radiator in a direction reverse to the normal flow of water through the radiator during the dislodging of sediment. 90

5. Inverting the radiator and forcing the solution downwardly therethrough so that the radiator tank may act as a sediment trap and so that the particles, when once dislodged, may drop by gravity away from the 95 radiator channels.

6. Clogging all openings of the radiator except the two hose connections in order to prevent loss of the solution and in order to seal the radiator against the pressure of the 100 flowing liquid.

The following elements are also vital to the attaining of all the objects hereinbefore stated, including the cleaning of a radiator in a minimum length of time:

105 1. Heating the solution to increase its activity.

2. Employing a pump which will indicate by its laboring the load which it is carrying.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope. 115

I claim as my invention:

1. A process of cleaning vehicle radiators, comprising the following steps: inverting 120 the radiator, plugging all openings to its interior except the water hose connections, pumping a solution adapted to remove scale without attacking the metal of the radiator, through the radiator in a direction reverse 125 to the normal flow of water through the radiator, and maintaining the said direction of flow constant during the removal of sediment.

2. A process of cleaning vehicle radiators, comprising the following steps: inverting 130

the radiator, plugging all openings to its interior except the water hose connections, pumping a solution adapted to remove scale without attacking the metal of the radiator, 5 through the radiator in a direction reverse to the normal flow of water through the radiator, maintaining the said direction of flow constant during the removal of sediment, and then flushing the dislodged sediment from 10 the radiator tank by a stream of water.

3. A process of cleaning vehicle radiators, comprising the following steps: inverting the radiator, pumping a solution adapted to remove scale without attacking the metal of the 15 radiator, through the radiator in a direction reverse to the normal flow of water through the radiator.

4. A process of cleaning vehicle radiators, comprising the following steps: inverting 20 the radiator, plugging all openings to its interior except two, and pumping a solution

adapted to remove scale without attacking the metal of the radiator, into one of said openings, causing the solution to flow, through the radiator in a direction reverse to the normal flow of water through the radiator. 25

5. A process of cleaning vehicle radiators, comprising the following steps: inverting the radiator, plugging all openings to its interior except two, pumping, under pressure, 30 a solution adapted to remove scale without attacking the metal of the radiator, into one of said openings, causing the solution to flow through the radiator in a direction reverse to the normal flow of water through the radiator, and maintaining said pressure substantially constant during cleaning of the radiator. 35

Signed this 13th day of April, 1928, in the county of Woodbury and State of Iowa.

JAMES M. ROBINSON.
